UNITED STATES PATENT OFFICE.

JOHN H. COX, OF ERIE, KANSAS.

HORSE HAY-RAKE.

SPECIFICATION forming part of Letters Patent No. 683,445, dated October 1, 1901.

Application filed January 31, 1901. Serial No. 45,481. (No model.)

To all whom it may concern:

Be it known that I, JOHN H. COX, a citizen of the United States, residing at Erie, in the county of Neosho and State of Kansas, have 5 invented a new and useful Horse Hay-Rake, of which the following is a specification.

My invention is an improved horse hay-rake; and it consists in the peculiar construction and combination of devices hereinafter 10 fully set forth and claimed.

One object of my invention is to effect improvements in the means for rotating the rake-head to discharge the rake-teeth of their load and for locking the rake-head with the 15 teeth in either operative or inoperative position.

Another object of my invention is to effect improvements in the construction of the rake-teeth and in the combination therewith of the 20 revoluble rake-head, which carries the rake-teeth.

In the accompanying drawings, Figure 1 is a perspective view of a horse hay-rake constructed in accordance with my invention. 25 Fig. 2 is an elevation of the same, partly in section. Fig. 3 is a detail perspective view showing the means for conveying power from the axle to the rake-head for revolving the latter and showing the means for locking the 30 rake-head with the teeth thereof in either operative or inoperative position. Fig. 4 is a detail plan view showing the axle, the sprocket-wheel thereon, the clutch member splined on the axle, the lock-bar, and the bell-crank lever connecting the latter with the splined 35 clutch member. Fig. 5 is a detail perspective view of a section of the rake-head and of one of the rake-teeth, showing the construction of the latter and the manner in which 40 the same is secured to the rake-head. Fig. 6 is a detail elevation, partly in section, showing the revoluble stop-disk having the brake-flange and the brake-spring bearing on said 45 brake-flange.

The frame 1 may be of any suitable construction. As here shown, it comprises a front cross-bar 2, side bars 3, which extend rearward therefrom at the ends of said cross-bar and are formed integrally therewith, and 50 a cross-bar 4, which is disposed at a suitable distance in rear of cross-bar 2 and has its ends secured on the side bars 3. Bearings 5

are secured to the side bars, and in said bearings is journaled a revoluble axle-shaft 6, on which are the wheels 7. Each of the said 55 wheels is loose on said axle-shaft, and said wheels are secured on said axle-shaft by means of the usual pawl-and-ratchet mechanisms, which are not here shown, as their construction is well understood by those 60 skilled in the mechanic arts, said pawl-and-ratchet mechanisms serving to lock the said wheels to the said axle-shaft and to permit the said wheels to slip and rotate idly on said axle-shaft when the rake is being turned. 65 The frame is provided with the usual tongueS.

A revoluble rake-head 9 is journaled in bearings 10 near the rear ends of the side bars 3. The said revoluble rake-head is provided with rake-teeth 11, which are more 70 fully described hereinafter, and the said revoluble rake-head is provided near its center with a disk 12, which is fast thereon. A sprocket-wheel 13 is also fast on the said revoluble rake-head and is located near the said 75 disk. In one of the faces of disk 12 is an annular groove 14, which is provided at two points with offsets 15 16, which, in connection with a locking-bar, hereinafter described, serve to lock the revoluble rake-gear with its 80 teeth in either operative or inoperative position.

A sprocket-wheel 17 is loose on the axle-shaft 6, is connected to sprocket-wheel 13 by an endless sprocket-chain 18, and is provided 85 on one side with a clutch member 19. A sleeve or collar 20 is splined on the axle-shaft, has an annular groove 21, and is further provided with a clutch member 22, which when in engagement with the clutch member 19 90 locks the sprocket-wheel 17 to the axle-shaft and when out of engagement therewith permits said axle-shaft to rotate independently of said sprocket-wheel 17.

A longitudinally-disposed bar 23 connects 95 the cross-bars 2 4 and the revoluble rake-head, the latter being also journaled in a bearing 24, with which said bar is provided. A locking-bar 25 is movable longitudinally on the bar 23 and is retained in position thereon by a guide 26. The front end of the lock-bar 25 is connected to a foot-lever 27, whereby said rod 25 may be operated, and the latter is provided at its rear end with an engag-

ing stud or pin 28, which rides in the annular groove 14 of disk 12 and is adapted to engage the offsets 15 16, which are disposed on opposite sides of said groove. A bell-crank 5 lever 29 is fulcrumed to the bar 23, is connected to the lock-bar 25 and operated thereby, as at 30, and said bell-crank lever engages the annular groove 21, with which the sleeve or collar 20 is provided. When said rod 25 is moved forward and caused to engage the offset 15, the sleeve or collar is clutched to the sprocket-wheel 17, and thereby the rake-head is rotated by the sprocket-wheels and chain which connect it to the 15 axle-shaft. When the rake-head has completed one revolution, the said offset 15, which forms a cam, by engagement with the stud or pin 28 of rod 25 moves said stud or pin against an offset 15^a, and thereby locks the revolute 20 rake-head against further rotation and disposes the rake-teeth in operative position. When it is desired to lock the rake-teeth in inoperative position, the rod 25 is moved rearward by the lever 27, while the rake-head is 25 being rotated and caused to engage the offset 16 in the disk 12. It will be understood that when the stud or pin of rod 25 is in engagement either with the offset 15^a or offset 16 the sleeve on the axle-shaft is unclutched 30 from the sprocket-wheel 17, and hence power is not conveyed from the axle-shaft to the revolute rake-head.

I house the operative connections hereinbefore described between the axle-shaft and 35 the revolute rake-head by a casing 31, which comprises two members 32 33, hinged together at one end, as at 34, adapted to engage said revolute rake-head and said axle-shaft and provided with hooks or other suitable 40 devices 35 for securing them together.

The seat 36 for the driver is supported by the cross-bar 4 of the frame, as shown.

In order to clear the rake-teeth of any hay which may adhere thereto when the rake-head is rotated in order to discharge a load in the formation of a windrow, I provide 45 cleaning-bars 37, which have their front ends secured to the frame 1 and which extend over and project rearwardly from the revolute 50 rake-head and are disposed at appropriate distances apart and between the rake-teeth.

Each rake-tooth 11 is bent reversely at its upper end, as at 38, then laterally at right angles, as at 39, and then outwardly at right 55 angles, as at 40, the reversely-bent portion 38 and terminal portion 40 being parallel with each other and passed through openings in the revolute rake-head, as shown, and said terminal portion 40 is screw-threaded and provided with a nut 41 to secure the tooth to the rake-head. Any other suitable securing means may be employed instead of the nut, and I do not limit myself in this particular. It will be understood that the 60 portions 38 40 of the teeth which pass through the openings in the rake-head and which are

substantially parallel effectually prevent the rake-teeth from turning in the rake-head.

On one side of the disk 12 is a segment-shaped brake-flange 42, which is engaged by 70 a brake-spring 43 at the rear end of the bar 23 while the rake-head is being revolved on the descent of the rake-teeth to retard the descent of the latter, and hence avoid the jar-ring or jerking of the rake-head which might otherwise result.

Having thus described my invention, I claim—

1. In a horse hay-rake, the combination of 80 a revolute rake-head, a disk revolute therewith, said disk having an annular groove on one side, a notch 16 communicating with said groove and offsets 15, 15^a on opposite sides of said groove, a revolute power element, a clutch to throw the same into and 85 out of gear, connections between said revolute power element and said revolute rake-head, to rotate the latter, a longitudinally-movable rod having a stud or pin in the groove of said disk to engage said notch and 90 offsets, and a connection between said rod and said clutch, whereby the latter is operated by the former, substantially as described.

2. In a horse hay-rake, the combination of 95 a revolute power-shaft, a revolute power element loose thereon, a clutch to lock said power element to said shaft, a revolute rake-head connected to and rotated by said power element, a stop-disk on said rake-head, a longitudinally-movable stop-rod 100 to engage said stop-disk, a brake element carried by said rod, and coacting with said stop-disk to retard the descent of the rake-teeth as the rake-head revolves, and a connection between the 105 said stop-rod and said clutch, substantially as described.

3. In a horse hay-rake, the combination of 110 a revolute power element, a loose sprocket-wheel, a clutch to lock the same to said revolute power element, a revolute rake-head, a sprocket-wheel fast thereon, an endless chain connecting said sprocket-wheels, a disk revolute with said rake-head, said disk having an annular groove on one side, a notch 115 16 communicating with said groove, and offsets 15, 15^a on opposite sides of said groove, a longitudinally-movable rod having a stud or pin in said groove, to engage said notch and offsets, for the purposes set forth, and a connection 120 between said rod and said clutch, whereby the latter is operated by the former, substantially as described.

4. In a horse hay-rake, the combination of 125 a revolute power element, a loose sprocket-wheel, a clutch to lock said sprocket-wheel to said power element, a revolute rake-head, a stop-disk and sprocket-wheel thereon, an endless chain connecting said sprocket-wheels, a longitudinally-movable stop-rod to engage 130 said stop-disk, a brake element carried by said longitudinally-movable stop-rod, said brake

element and said disk coacting to retard the descent of the rake-teeth as the rake-head revolves, and a connection between said stop-rod and said clutch, whereby the latter is operated by the former, substantially as described.

5. In a horse hay-rake, the combination of a rake-head and means to rotate the same, a stop element therefor, a stop-rod to engage 10 said stop element, to lock the rake-head against rotation, and a brake-spring carried by said stop-rod, said brake-spring coacting with said stop element to retard the descent of the rake-teeth as the rake-head revolves, 15 substantially as described.

6. A rake-tooth having at its upper end the downwardly-bent portion 38 substantially

parallel therewith and disposed in rear thereof, the portion 39 bent outwardly from the lower end of said portion 38, and the portion 20 40 bent upwardly from said portion 38, said portions 38, 40 being parallel with each other and adapted to be secured in transverse openings in a rake-head, said portion 39 being adapted to bear against the lower side of the 25 rake-head, substantially as described.

In testimony that I claim the foregoing as my own I have hereto affixed my signature in the presence of two witnesses.

JOHN H. COX.
